PICKET FOR A FENCE

Andrew Calladine, 26 Marydon Crescent, Agincourt,
Ontario, Canada

Filed June 4, 1964, Ser. No. 80,287

Term of patent 14 years

(Cl. D28—1)

FIG. 1 is a front elevation view of the picket showing my new design;

FIG. 2 is a side edge view thereof;

FIG. 3 is a rear elevational view thereof;

FIG. 4 is an upper end view thereof; and

FIG. 5 is a lower end view of the same.

I claim:

The ornamental design of a picket for a fence, as shown.
